(57) **CLAIM**

The ornamental design for a single-pronged pan handle for die-cast cookware, as shown and described.

DESCRIPTION

FIG. 1 is a front perspective view of a single-pronged pan handle for die-cast cookware, showing my new design;

FIG. 2 is an exploded front perspective view thereof;

FIG. 3 is an exploded bottom perspective view thereof;

FIG. 4 is an exploded top plan view thereof;

FIG. 5 is an exploded bottom plan view thereof;

FIG. 6 is an exploded right-side elevational view thereof, the left-side elevational view being a mirror image thereof;

FIG. 7 is an exploded rear elevational view thereof;

FIG. 8 is a front elevational view of the single-pronged pan handle, the die-cast cookware omitted for clarity of illustration; and,

FIG. 9 is a cross-sectional partial view of my new design along line 9 as shown in FIG. 4.

The regular broken lines depict portions of the cookware, handle and a screw that form no part of the claimed design. The dot-dash broken lines depict boundaries of the claimed design and form no part of the claimed design.
